UNITED STATES PATENT OFFICE.

WILLIAM C. SCHEU, OF GRAND JUNCTION, COLORADO, ASSIGNOR OF ONE-HALF TO
S. B. HAMPTON, OF CORONA, CALIFORNIA.

ORCHARD-HEATER.

1,148,804.

Specification of Letters Patent. Patented Aug. 3, 1915.

Application filed October 12, 1914. Serial No. 866,408.

To all whom it may concern:

Be it known that I, WILLIAM C. SCHEU, a citizen of the United States, residing at Grand Junction, in the county of Mesa and State of Colorado, have invented a new and useful Orchard-Heater, of which the following is a specification.

This invention relates to heaters for protecting orchards from frost, and the main object of the invention is to provide a heater for this purpose with a stack of sufficient height to give perfect combustion and resulting high heat efficiency, but in which the stack is so constructed that it may be collapsed or lowered when not in use.

Another object of the invention is to provide means for cleaning the stack in the collapsing operation.

A further object of the invention is to provide means for reducing or adapting the heater opening to enable different size stacks to be fitted thereto.

This application relates to an improvement on the type of orchard heater shown in my application Serial No. 842,361, filed June 2, 1914, which claims certain features herein disclosed.

The accompanying drawings illustrate the invention, and referring thereto:

Figure 1 is a side elevation, partly broken away, of a heater provided with my improved stack. Fig. 2 is a vertical section of the stack in collapsed position. Fig. 3 is a side elevation of the heater in covered condition. Figs. 4 and 5 show modifications.

The heater may be of any suitable type, comprising, for example, a fuel receptacle 1, having a cover 2, formed with an opening 3, for communication with the stack. Around said opening the cover is provided with an upturned flange or collar 4, to receive and support the stack or the stack supporting means.

In the present instance I have shown a reducer fitted on this collar, said reducer having a downturned flange 6, surrounding and fitting on said collar, and having an upturned flange or portion 7 adapted to fit within the lower end of the stack. In order to provide a tight joint, the engaging flanges 4 and 6 are preferably tapered and flared, respectively, so that they may be forced into tight contact, making a substantially air tight joint or connection between the stack and the receptacle 1.

The stack is composed of a plurality of sections, including a lower section 9, fitted on the reducer aforesaid, and one or more upper sections 10, the several sections telescoping or nesting on one another. I prefer to make the upper sections telescope or nest within the lower ones, each section being slightly smaller than the next lower section, so as to permit of such telescoping. I also prefer to provide means for frictional engagement between the sections, for example, beads 11 formed on the sections near the ends thereof, and adapted to engage one another when the sections are drawn out to full length position, as shown in Fig. 1, to retain the parts in such position until they are forcibly collapsed.

The upper stack section 10 is preferably provided with means, such as a bar or strip 13 extending across the stack, and secured by spot welding or otherwise, to the stack wall, to serve as a handle in raising or lowering the stack.

The fuel receptacle 1 may be provided with any suitable means indicated at 14, for supplying or admitting air thereto, for supporting combustion or partial combustion. I prefer to also provide the stack with air admission means consisting of openings 16 in the wall of the lowermost section 9, said openings having louvers 17, formed by bending out or bulging out the wall of the stack directly over each opening, to form deflectors whereby the air is directed properly into the opening, and the openings are protected from entrance of water during rainy weather.

As so constructed, the lower stack section operates as a combustion chamber, wherein the vapor generated by partial combustion in the receptacle 1, is completely burnt by further combustion with air admitted through the openings 16. In case very heavy oil is used however, there will, in general, be more or less deposition of carbon on the lower part of the wall of this section, and the above described collapsible construction of the stack has the further advantage, in this connection, that the next inner or higher section, in sliding within the lower section when the stack is being collapsed, scrapes and cleans such deposit off of the lower section.

Cover 2 is preferably provided with a flange 2' making a substantially airtight joint with the receptacle 1, so that the re-

ceptacle and stack are in substantially airtight connection. A suitable cover 20 is provided for covering the stack when not in use, and said cover may also be constructed to cover the whole heater, as shown in Fig. 3, said cover in that case having an apron or frusto-conical extension 21, which extends over the receptacle cover 2, and serves as a means of protection against the weather. I also prefer to provide this stack cover with means for engaging the stack, so as to enable the stack to be raised or extended by simply lifting the cover. For this purpose the cover 20 may be provided with depending hooks or lugs 22, adapted to engage under lugs 23 on the inner section of the stack, so that on lifting the cover, said inner section will also be lifted. By turning the cover, the lugs 22 thereon may then be disengaged from the lugs 23 on the stack section, and the cover then removed from the stack. As shown in Fig. 4, the cover 20 may be made without the extension aforesaid. Said cover has a handle 20'.

The construction above described enables the stack to be made comparatively high, so as to give a strong draft effect when the heater is in use, while permitting the stack to be made low when the heater is not in use, so that the device is then brought to compact form suitable for storage, and for protection from the weather. In some cases I may fit the sections together in the manner shown in Fig. 5, the stack then comprising a lower section 9' having perforations 16' for admission of air, and one or more upper sections 10' fitted to one another and to the section 9' by frictional slip joints at their ends. With this construction it is necessary to assemble or separate the sections in putting up or taking down the stack, and the device is therefore less convenient, though less expensive than the preferred form of the invention shown in Fig. 1.

The stack, as shown in Fig. 1, preferably communicates directly with the interior of the receptacle 1, and the air inlet means 14 in the cover of the receptacle is preferably formed as an opening having a valve or closure 14' whereby the admission of air may be regulated so as to provide for only partial combustion in the receptacle 1, and resulting generation of combustible vapor therein. In order to limit or confine this partial combustion I prefer to provide a wall member 24 within the receptacle, forming a combustion chamber extending beneath the air inlet means 14 and also beneath the stack to any desired extent, that is, either partially or wholly beneath the stack, so as to communicate directly with the air admission means and with the stack, this wall member 24 being perforated as at

25 for communication of liquid and vapor from the receptacle to this combustion 65 chamber.

What I claim is:

1. A stack for orchard heaters, comprising a plurality of sections, of different diameter, telescoping and nesting on one another, 70 and provided near their ends, with beads, the beads on adjacent sections frictionally engaging one another to hold the stack in extended position.

2. In an orchard heater, the combination 75 with the fuel receptacle, and a cover therefor having an opening and provided with a flange around said opening, of a reducer fitting on and secured to said flange and having an upwardly extending flange, and 80 a stack fitting on said upwardly extending flange on the reducer.

3. In an orchard heater, the combination 85 of a fuel receptacle, a cover therefor, a stack mounted on said cover and communicating directly with the interior of said receptacle, said cover being provided with air admission means, and a wall member within said receptacle, and extending beneath 90 said air admission means and beneath said stack, to form a combustion chamber communicating directly with the air admission means and with the stack, said wall member being perforated at both upper and lower 95 portions thereof, to establish communication between the interior of the receptacle and said chamber.

4. In an orchard heater, the combination 100 with a fuel receptacle and a cover therefor, of a collapsible stack mounted on said cover, and a cover for said stack provided with 105 means for detachably engaging said stack, to enable the stack to be lifted by its cover, and to enable the cover to then be removed from the stack.

5. In an orchard heater, the combination 110 with the fuel receptacle and cover therefor, of a collapsible stack mounted on said cover, and comprising a plurality of sections provided near their ends with beads engaging one another to hold the stack in extended position, and means connected to the uppermost stack section for lifting the stack.

6. In combination with an orchard heater having a fuel receptacle, a cover therefor, 115 and a stack mounted on said cover, a protective cover removably mounted on said stack and having an apron extending over the fuel receptacle and its cover.

In testimony whereof I have hereunto set 120 my hand, at Los Angeles, California, this 30th day of September, 1914.

WILLIAM C. SCHEU.
